CLOSURE

Nicholas H. Wierk, Jr., Oakland, Calif.

Application March 18, 1935, Serial No. 11,610

1 Claim. (Cl. 20—68)

My invention relates to means especially adapted to be installed on doors, windows or comparable structures, in order to complete the sealing of the openings and to preclude leakage thereby.

An object of my invention is to provide a closure which can readily and simply be installed on a door or window, whether standard or not.

Another object of my invention is to provide 10 a closure which is very simple mechanically, in order to lessen the cost of fabrication and installation.

A further object of my invention is to provide 15 a closure which will operate automatically to act as a seal when the door or window to which it is attached is in closed position and which will move to an inoperative or non-sealing position when the structure to which it is attached is in open position.

An additional object of my invention is to provide 20 a closure which can serve as an original installation on a door or window and which can readily be applied to the obverse or the reverse face of a door or a window already in place.

The foregoing and other objects are attained 25 in the embodiment of the invention illustrated in the drawing, in which

Fig. 1 is a side elevation of a closure constructed in accordance with my invention and applied 30 to the lower edge of a door, portions of the figure being broken away to reduce the size thereof.

Fig. 2 is a cross-section, the plane of section being generally on a longitudinal, vertical plane through the central portion of the closure of my 35 invention, parts of the structure being broken away to disclose the construction thereof.

Fig. 3 is a fragmentary view showing in perspective the closure of my invention applied to the obverse side of a door.

Fig. 4 is a fragmentary view showing in perspective the closure of my invention applied to the reverse side of a door.

Fig. 5 is a cross-section showing in plan the operation of the closure of my invention as it 45 is applied to a door.

Fig. 6 is a cross-section of a door to which the closure of my invention is applied in an alternative manner.

In its preferred form, the closure of my invention 50 comprises a frame which is designed to be attached to a structure such as a door or a window, the frame carrying a sealing strip which is movable with respect thereto and which in projected position is intended to seal the remaining 55 opening between the door and the floor, for in-

stance, and which in retracted position is intended to clear the floor by a substantial amount, the sealing means being operated by an actuator which is moved longitudinally of the frame by contact with the door frame when the door is in closed position. The motion of the actuator is preferably transmitted to the sealing strip by a plurality of leaf springs which are attached to the frame, to the actuator and to the strip in such a way that they resiliently urge the strip 10 to project from the frame upon longitudinal displacement of the actuator and likewise restore the strip to retracted position upon release of the actuator.

Although the closure of my invention is adapted 15 for use in various different environments, especially on closures of the sliding and of the leaf type, such as sliding doors, casement windows and hinged doors, and while it is susceptible to various modifications in detail to fit it for service in special circumstances, I have chosen 20 to illustrate it herein as it is applied to a door of the leaf type. A door of this character is disclosed in Fig. 5, wherein there is shown a door frame 6 having a jamb 7 adjacent which there is fastened a hinge or butt 8 likewise secured to the door 9, so that the door swings in the direction of the arrow 11. As illustrated, the door is in open position, so that the inner edge 12 of the door is spaced away from the jamb 7.

In accordance with my invention, I preferably 25 provide the lower edge of the door 9 with a closure, generally designated 13. The closure includes an actuator, one portion 14 of which projects from the general body of the closure in order to abut and contact a button 16 embedded 30 in the jamb 7 and which, upon closing movement of the door 9, translates the actuator 14 longitudinally of the closure 13 and thereby causes an actuation thereof. When the door is 35 moved into open position, shown in Fig. 5, the actuator 14 is released, leaving its contact with the button 16, and the mechanism is moved to its inoperative or retracted position.

In the form of closure shown herein, I preferably 40 provide a mounting frame 21 which is in the form of a metal channel U-shape in cross-section. The channel is of considerably greater length than width or thickness, and is preferably 45 attached either to the obverse face of the door, as shown in Fig. 3, or to the reverse face of the door, as shown in Fig. 4. To effect such an attachment, the channel is preferably pierced to provide a plurality of different sized apertures 22 and 23. These apertures pass through both legs 50 55

24 and 26 of the channel in alignment, but are of different size in each leg. This is for the purpose of permitting the head of a screw to pass through the enlarged aperture 22 in the leg 26, 5 for example, but to engage the smaller aperture in the other leg 24. Conversely, the aperture 23 in the leg 26 corresponds and is in alignment with the enlarged aperture 22 in the leg 24. In this way, the mounting member is interchangeable for 10 use on either side of the door.

Adapted for movement relative to the channel 21 is a sealing means, generally designated 27, which preferably includes a smaller channel 28, the legs 29 and 31 of which tightly grip a strip 15 32 of any suitable material, such as rubber. The channel 28 is freely movable into and out of the channel 21, in order that the sealing strip 32 can be retracted to clear the floor above which the door swings, or can be expelled in order to come 20 into contact with such floor. Preferably, the length of the channel 27 and of the strip 32 is substantially equal to the length of the door. In order to retain the channel 27 in its desired path 25 of motion, and in order to provide it with an automatic actuation depending upon the position of the door 9, I preferably provide an actuator 36, which comprises a relatively long metallic rod extending throughout the length of the channel 21 and guided for rectilinear movement therein by 30 means of blocks 38 which are held to the channel 21 by suitable fastenings 39. The rod 36 is cut away to provide guide-ways 42 which make a freely sliding fit with the blocks 38. The extreme end of the rod 36 is preferably bored and threaded, 35 as at 43, in order to receive the stud 14 having an enlarged head 44 for contact with the button 16. Because of the threaded connection between the rod 36 and the stud 14, any desired amount of projection can be obtained in order to adjust 40 the device.

To relate the rod or actuator 36 with the channel or sealing strip 27, and in order to maintain the parts normally in a selected position, I preferably provide a yielding motion transmitting 45 means intermediate the actuator and the sealing means, which preferably takes the form of a plurality of leaf springs 46 which are spaced apart at suitable intervals along the channel 21. Conveniently, one end of each leaf spring 46, for instance, is fastened under the head of a stud 39 and abuts a block 38, while the other end of each leaf spring is attached by a fastening 50 to the rod 36. In the present instance each leaf spring is reinforced by a spring plate 47, both of which 55 are anchored adjacent the middle of the compound spring so formed, by a fastener 48 which passes through the springs 46 and 47 and through the channel 27. When the rod 36 is translated,

say toward the left in Fig. 2, and since one end of each spring is anchored by a fastening 39, the central portion of each spring is buckled from the solid line position shown in Fig. 2 into the dotted line position 51 shown in such figure, thereby translating the sealing strip 32 transversely of the channel 21 into yielding or resilient contact with the floor. Since there is a plurality of yielding intermediate springs, slight irregularities in installation or in the floor surface are compensated for by different degrees of yielding of the springs. 10

When the actuator 36 is released from contact with the button 16 by opening of the door, for instance, the inherent resiliency of the springs 15 causes them to reassume the solid line position shown in Fig. 2 and to restore the strip 32 to retracted position.

In installing the device, the channel 21 is secured either to the obverse face 52 of a door, as 20 shown in Fig. 2, or to the reverse face 53 of a door, as shown in Fig. 4, and in either instance, after installation of the closure itself has been made, I preferably provide a finishing strip 54 which can be provided with any suitable surfacing finish, either to match the door or otherwise, which is simply slipped into position with a depending flange 56 thereof frictionally engaged between the channel 21 and the face 52 or 53 of the door. This member 54 is primarily for the 30 purpose of appearance and can be omitted in the event the channel 21 itself carries an appropriate surface finish.

In certain instances it is preferable not to affix the closure to a face of the door, and in those 35 instances I preferably provide the lower portion of the door with a recessed channel or rabbet 57 which extends for substantially the full width of the door and which is of sufficient size conveniently to receive the channel 21 frictionally. In 40 addition, the channel is preferably held in place by ears 58 which are upturned from each end of the channel and which are suitably pierced as at 59 to receive screws or other fastening means.

I claim:

A closure for a door comprising a frame, a sealing strip movable bodily with respect to said frame, a plurality of apertured blocks on said frame, an actuator having slots therein encompassing said blocks to guide said actuator, a plurality of leaf springs each being perforated at one end adjacent to one of said blocks, and being secured at the other end to said actuator and adjacent the center to said sealing strip, and a common fastener for each of said springs passing through the perforation therein, through the aperture in said block and through said frame. 45
